UNITED STATES PATENT OFFICE.

ARTHUR L. SCHEYING, OF CHICAGO, ILLINOIS.

FURNACE WALL.

Application filed March 26, 1924. Serial No. 701,943.

To all whom it may concern:

Be it known that I, ARTHUR L. SCHEYING, a citizen of the United States, residing at Chicago, in the county of Cook and State 5 of Illinois, have invented certain new and useful Improvements in Furnace Walls, of which the following is a specification.

This invention relates to walls for furnaces, and, particularly walls which are exposed to high temperatures, such as walls of boilers, metallurgical and steel furnaces, and the like. One of the objects of the invention is to provide a wall arranged so that injuries thereto may be conveniently and 10 quickly repaired, particularly without disturbing or injuring such portions of the wall as are not in need of repairs. Another object of the invention is to provide a wall which can be quickly and conveniently assembled and which is inexpensive and dependable.

This invention is a modification of the invention disclosed by my patent application Serial No. 613,110, filed January 17, 1923, 15 and for details of the invention which are not material to this application reference may be had to the said former application.

Of the drawings of the application Fig. 1 is an elevation of a portion of the outer wall; Fig. 2 is a sectional view along the line 2—2 of Fig. 1; Fig. 3 is an elevation of a portion of the inner wall; Fig. 4 is a detail view of a portion of Fig. 2; and Fig. 5 is an elevation of a portion of the edge of 20 the double wall; all of which embody features of my invention.

In general, the wall which I disclose is a combination of two walls comprising an inner wall 10 and an outer wall 11, having an air space 12 between the two walls. The walls are substantially air tight and the spaces between the walls are sealed in any suitable manner. A frame is provided for supporting the walls. While any suitable frame may be used, I prefer for the purpose 25 uprights composed of a pair of L-beams 13, which are riveted together with a plate 14 between. The plate extends inwardly and outwardly each side of the outer wall 11. The outer edge of the plate has slots 26 through which pass straps 27, and in these straps are screws 28 by means of which the sections of the wall 11 are pressed firmly 30 against the flanges 29 of the beams 13. In

this manner the sections of the wall 11 may be very conveniently removed or installed. To remove a section of the walls it is necessary only to remove the straps 27.

The plates 14 are connected together by means of pipes 16 through which pass bolts 17. The bolts also pass through the plates and the plates are thus bolted firmly to the ends of the pipes by means of the nuts 18. In this manner a frame is formed which supports the outer wall and forms a support for preventing any horizontal movement of the inner wall, and by removing the bolts 17, the outer wall which is formed in sections or portions thereof, may be conveniently removed, so as to have free access to the outer 70 side of the inner wall.

The inner wall is preferably composed of suitable fire bricks 20 cemented together with suitable heat resisting cement, the dimensions of the bricks and the wall being 75 suitable for the particular purpose. Positioned at suitable places in the wall 10 are bonding blocks 21, also made of heat resisting material and which extend into or through the wall 10. These bonding blocks 80 have projections 22 which extend into the space 12 between the two walls. These projections are suitably clamped to the framework of the walls so as to hold them firmly 85 in place and to prevent displacement thereof by air pressure or other warping tendencies, or during any repairs of the wall.

The means which I prefer for holding the bonding blocks in place comprises clips 23 which are formed in two complementary 90 pieces and are adapted to be bolted together by means of bolts 24 so that the outer ends 25 of the clips extend around and clamp loosely the tube 16, while the inner ends clamp the projections 22. In this manner 95 the bonding blocks are held from displacement with reference to the frame but slight movement thereof is allowed, such as would result from longitudinal or rotary movement of the clips 23 on the tubes 16. The bonding blocks, however, are held firmly against horizontal movement with reference to the wall, and any bowing or bending of the wall 100 is thus prevented.

If, however, the bricks of the inner wall 105 are injured by the intense heat of the fire so that it is necessary to repair the wall, the outer sections 11 of the wall opposite the

injured place may be removed, if desired, and the particular bricks which are injured can be readily driven out from the wall or removed in any suitable manner without disturbing the remainder of the wall; and any bonding blocks that need to be replaced may be quickly removed, and bricks and blocks may then be substituted without in any way injuring or disturbing the remainder of the wall.

I claim as my invention:

1. A vertical furnace wall comprising a plurality of fire blocks in combination with a plurality of bonding blocks interspersed among said fire blocks and forming a vertical wall, and means for holding said bonding blocks in place, said means comprising a frame work, a bar fixed to said frame work, and clips arranged to detachably clasp said bar and the ends of said bonding blocks.

2. A furnace wall comprising a plurality of blocks in combination with a plurality of bonding blocks interspersed among said first mentioned blocks, and means for holding said bonding blocks in place, said means comprising a frame work, a pipe fixed to said frame work and clips arranged to detachably clasp said pipe and the ends of said bonding blocks, said bonding blocks having enlarged ends projecting beyond the plane of said wall, and each of said clips comprising two complementary pieces, one end of each piece adapted to grasp said projection and the other end of each piece adapted to grasp said pipe.

3. A furnace wall comprising a plurality of furnace wall blocks, in combination with a plurality of bonding blocks interspersed among said furnace wall blocks, and means for holding said bonding blocks in place, said means comprising a pair of vertical beams, and horizontal pipes positioned adjacent said beams and fixed thereto, said bonding blocks being connected to said pipes.

4. A furnace wall comprising a plurality of furnace wall blocks in combination with a plurality of bonding blocks interspersed among said furnace wall blocks, and means for holding said bonding blocks in place, said means comprising a pair of vertical beams, a flange projecting from each beam, horizontal pipes positioned adjacent said beams, a bolt passing through each of said pipes and each of said flanges for bolting firmly together said beams and pipes, and detachable clips connecting said pipes with the respective bonding blocks.

5. A furnace wall comprising an inner wall composed of heat resisting materials and an outer wall composed of detachable segments, and a frame work connecting said two walls, said frame work comprising vertical beams positioned between the sections of said outer walls, means for detachably fastening said outer walls to said beams, and

means for fastening said inner walls to said beams.

6. A furnace wall comprising an inner wall composed of heat resisting materials and an outer wall composed of detachable segments, and a frame work connecting said two walls, said frame work comprising vertical beams positioned between the sections of said outer walls, means for detachably fastening said outer walls to said beams, 75 horizontal bars rigidly connecting said vertical beams, and means for connecting said horizontal bars with said inner wall.

7. A furnace wall comprising an inner wall, and an outer wall composed of detachable sections, a frame work connecting said two walls, said frame work comprising vertical beams, and means for connecting said beams to the inner wall, and means for pressing said sections against said beams.

8. A furnace wall comprising an inner wall, and an outer wall composed of detachable segments, a frame work connecting said two walls, said frame work comprising vertical beams, means for connecting said beams to the inner wall, and means for pressing said sections against said beams, said latter means comprising flanges projecting outwardly from said beams, straps projecting angularly from said flanges and outside of said sections, and means associated with said straps for pressing said sections away from said straps and towards said beams.

9. A furnace wall comprising an inner wall, and an outer wall composed of detachable segments, a frame connecting said two walls, said frame comprising vertical beams, means for connecting said beams to the inner wall, and means for pressing said sections against said beams, said latter means comprising flanges projecting outwardly from said beams between and beyond said sections, said flanges having openings therein, straps projecting through said openings and extending in each direction in front of said sections, and screws threaded into said straps and adapted to press against said sections.

10. The combination of two walls, vertical beams mounted between said walls, said beams having vertical flanges extending towards one wall, means for connecting said flanges to the adjacent wall, said beams having vertical flanges projecting beyond the other wall, and means fixed to said latter flanges for pressing the outer wall towards said beams.

11. A furnace wall comprising a plurality of furnace wall blocks in combination with a plurality of bonding blocks interspersed among said furnace wall blocks, and means for holding said bonding blocks in place, said means comprising beams positioned adjacent to said wall, and pipes fixed

angularly to said beams, said bonding blocks being connected to said pipes.

12. A furnace wall comprising an inner wall and an outer wall composed of detachable segments, a framework between and connecting said two walls, said framework comprising beams substantially parallel

with said inner wall, means for connecting said beams to the inner wall, and means for pressing said sections against said beams. 10

In testimony whereof, I hereunto set my hand.

ARTHUR L. SCHEYING.
